SILAS Y. IVES, OF MERIDEN, CONNECTICUT.

Letters Patent No. 81,509, dated August 25, 1868.

IMPROVED CHEESE-PRESS.

The Schedule referred to in these Letters Patent and making part of the same.

TO ALL WHOM IT MAY CONCERN:

Be it known that I, SILAS Y. IVES, of Meriden, in the county of New Haven, and State of Connecticut, have invented a new Improvement in Cheese-Press; and I do hereby declare the following, when taken in connection with the accompanying drawings, and the letters of reference marked thereon, to be a full, clear, and exact description of the same, and which said drawings constitute part of this specification, and represent, in—

Figure 1, a front view,

Figure 2 a longitudinal central sectional view, and in

Figure 3 the same sectional view in a different position.

This invention relates more particularly to that class of presses used by dairymen, commonly called "cheese-presses," but is alike applicable to other purposes, and the invention consists in the arrangement of the lower platen upon a vertical-sliding frame, upon which said frame is arranged a drum at opposite ends, and the said drums caused to revolve, as the platen descends, by means of a rack on the frame of the press and a pinion on the shaft of the drum, and upon the upper platen a single drum is arranged, from which a band extends to each of the said two drums, so that as the two platens descend, the drums on the lower platen, revolving, wind up the bands attached to the upper platen, so as to draw the upper platen gradually to the lower, as the two descend, the drum on the upper platen being for the adjustment of the platens one upon the other, so that the thing to be pressed, placed upon the lower platen, and the platens allowed to descend, the upper platen is drawn down on to the thing to be pressed, the weight of the thing to be pressed thus adding to the pressure.

To enable others to construct and use my improvement, I will proceed to describe the same, as illustrated in the accompanying drawings.

A is the base or bed of the press; B B, two uprights, supported by braces C, and tied at their upper end by cross-bars D.

E, the lower platen, is fixed upon two vertical slides, F, which move up and down freely in the uprights B, and in suitable bearings on the slides, F, or on the platen E.

Two shafts G are arranged, provided with pinions H, and on the side of the uprights are arranged corresponding racks I, so that as the slides F and platen E move up and down, the pinions and their shaft are accordingly turned, the two shafts forming drums upon which to wind the bands or cords L.

M, the upper platen, moves freely up and down between the slides F, and on the said upper platen is arranged a drum, N, upon the shaft of which a ratchet, P, is fixed, into which a pawl, R, operates.

The two bands, L, extend up through the upper platen, and are attached to the drum N, so that by turning the drum N the two platens are caused to approach each other, and are held in position by the pawl R, operating in the ratchet P.

From the upper platen, cords or bands S extend up to the drum T, so that by turning the said drum T, the whole movable part of the press is drawn up, as from the position in fig. 3 to that in fig. 1, or lowered accordingly, and when so raised is held in position by a pawl, U, operating in the rack W on the drum T, as seen in fig. 1.

This completes the construction of the press. Its operation is as follows:

Place the thing, Z, to be pressed, upon the lower platen E, as in fig. 1, when all the parts are held up by the pawl U. If it is necessary, for the insertion of the thing Z, that the platens be opened wider, release the drum N by raising the pawl R, and the lower platen will descend, while the upper platen is held by the pawl U, and when the lower platen has descended so as to open sufficiently between the two platens, arrest its further descent by dropping the pawl R into the ratchet P, or, if the space be too wide, reverse the operation, and draw up the lower platen.

The thing to be pressed being placed on the lower platen, and adjusted as described, raise the pawl U, which supports all the movable parts, and allow them to descend. In descending, the drum N, it will be noticed, is held fast by the pawl R while the lower drums are being turned by their pinions H, travelling down their

respective racks I, and thus turning, the bands L are wound upon the drums T, so as to draw the lower platen nearer to the upper platen. The diameter of the pinions being much larger than the diameter of their drums, the power which is exerted over the drums to wind the bands thereon is proportionate to the diameter of the pinions to the drums, the weight of the movable parts and the thing to be pressed adding to the force which causes the whole to descend. The power, therefore, exerted by the descent, as described, is very many times the weight of the thing to be pressed, and is self-adjusting, for so fast as the thing to be pressed is compressed or diminished in thickness, the platens descend, and consequently maintain the same pressure so long as the thing to be pressed remains therein. Having been sufficiently pressed, raise the parts, by means of the drum T, before described, and, in so raising, the belts from the lower drums are released in proportion as they were drawn up, consequently opening the two platens, so that after being raised a short distance, the thing pressed may be removed.

Having fully described my invention, what I claim as new and useful, and desire to secure by Letters Patent, is—

1. The arrangement of the two platens, M and E, combined with the drums G and bands L, so as to operate, by the descent of the platens, substantially as specified.
2. In combination with the above, I claim the drum M, operating as described.
3. In combination with the subject-matter of the first clause, I claim the bands S and drum T, arranged so as to operate substantially as specified.

S. Y. IVES.
